DESIGN FOR A COMBINED RODENT AND INSECT EXTERMINATOR

William F. Ramsay, Kerrville, Tex.

Application April 18, 1938, Serial No. 76,590

Term of patent 3½ years

To all whom it may concern:

Be it known that I, William F. Ramsay, a citizen of the United States, residing at Kerrville, in the county of Kerr and State of Texas, have invented a new, original, and ornamental Design for a Combined Rodent and Insect Exterminator, of which the following is a specification, reference being had to the accompanying drawing, forming part thereof.

Figure 1 is a side view of a combined rodent and insect exterminator showing my new design.

Figure 2 is a view of one end of the exterminator shown in Figure 1; and

Figure 3 is a view of the other end of the same.

I claim:

The ornamental design for a combined rodent and insect exterminator, as shown.

WILLIAM F. RAMSAY.
